US00D865808S

(12) **United States Design Patent** (10) **Patent No.:** **US D865,808 S**
(45) **Date of Patent:** **** Nov. 5, 2019**

(54) **PORTION OF A COMPUTER SCREEN WITH AN ICON IMAGE**

(71) Applicant: **Intermedia Labs, Inc.**, New York, NY (US)

(72) Inventors: **Ruslan Yusupov**, New York City, NY (US); **Darren Scott Cummings**, London (GB); **Russell Scott Wyner**, Brooklyn, NY (US); **Marcus Eckert**, Berlin (DE)

(73) Assignee: **Intermedia Labs, Inc.**, New York, NY (US)

(**) Term: **15 Years**

(21) Appl. No.: **29/640,096**

(22) Filed: **Mar. 12, 2018**

(51) LOC (12) Cl. **14-04**

(52) U.S. Cl.

USPC **D14/490**; D14/489; D14/492

(57) **CLAIM**

The ornamental design for a portion of a computer screen with an icon image, as shown and described.

DESCRIPTION

FIG. 1 is a front view of a portion of a computer screen with an icon image showing our new design; and,

FIG. 2 is a front view of a portion of a computer screen with an icon image showing our new design.

The broken lines in FIGS. 1 and 2 form no part of the claimed design. The long dash short dash lines illustrate the portion of the computer screen on which the icon image is displayed and the long dash short dash lines for no part of the claimed design.

1 Claim, 2 Drawing Sheets
